DEVICE FOR PREVENTING FALSE WEFT
DETECTIONLeon A. Carron, Worcester, Mass., assignor to
Crompton & Knowles Loom Works, Worcester,
Mass., a corporation of Massachusetts

Application September 8, 1949, Serial No. 114,557

6 Claims. (Cl. 139—273)

1

This invention relates to improvements in electrically indicating side slipping weft detectors for weft replenishing looms and it is the general object of the invention to prevent the detector from giving a false indication when it is moved forwardly incident to a weft replenishing operation of the loom.

Multicolor weft replenishing looms are generally made with the weft detector at the magazine end. This construction requires that the detector be moved out of the path of the incoming bobbin at the time of weft replenishment. When a weft detector of the side slipping type is employed there is likelihood that the forward motion of the detector made necessary to clear the path for the incoming bobbin may produce a false indication of weft exhaustion.

It is an important object of the present invention to provide a lock lever on the weft detector mechanism normally in non-locking position to permit the detector to perform its detecting function on non-replenishing beats of the loom but so controlled as to move into locking relation with respect to the detector when the latter is moved forwardly by the transerrer arm and thereby prevent a false indication.

With these and other objects in view which will appear as the description proceeds, the invention resides in the combination and arrangement of parts hereinafter described and set forth.

In the accompanying drawings, wherein a convenient embodiment of the invention is set forth, Fig. 1 is a side elevation of part of a weft replenishing loom, the lay and shuttle being in cross section and the weft detector being in normal position.

Fig. 2 is an enlarged plan view looking in the direction of arrow 2, Fig. 1, the bolt which holds the detector to its carrier being in section,

Fig. 3 is a view similar to Fig. 2 but showing the detector in its forward position with the locking lever moved to locking position, and

Fig. 4 is an enlarged detailed vertical section on line 4—4, Fig. 3.

Referring to Fig. 1, the loom frame 10 supports the foot 11 of a weft replenishing mechanism which includes in its construction a transerrer arm 12. The latter is pivotally mounted on a stud 13 secured to stand 11 and has a depending foot 14 provided with a laterally extending lug 15.

Secured to the stud 13 in stationary position is a stand 16 which holds a support 17 in stationary adjusted position. The support has a hub 18 in which is slidably mounted a rod 19 the forward

2

end of which, at the left as viewed in Fig. 1, is secured to a U-shaped carrier 20. The latter has an upstanding arm 21 through which passes a guide rod 22 secured to the support 17. The carrier has a forward upright arm 23 to which is attached the forward end of a tension spring 24 the rear end of which is attached as at 25 to a part of the support 17. The effect of spring 24 is to hold a carrier 20 in rearward position, or to the right as viewed in Fig. 1, but permit the carrier to slide forwardly on a replenishing beat of the loom. On such a beat the transerrer arm 12 will rock in a clockwise direction around stud 13 and the lug 15 will engage the arm 23 and move the carrier forwardly.

The weft detector mechanism, designated generally at D, comprises a plate 30 which may be made of sheet steel and supports at its rear end a stud 31 on which is pivotally mounted a detector finger 32. The latter finger has slidably mounted therein a detector wire 33 having a detector tip 34 for engagement with the bobbin in the shuttle. The tip 34 is normally held in rear position but upon engagement with a full supply of weft will slide forwardly in the finger 32 without causing angular motion of the latter. When, however, the detector engages a depleted bobbin it will slide to the right and move to the dotted line position shown in Fig. 2 against the action of a spring 35 which surrounds stud 31 and is operatively connected at one end to the finger 32 and at its other end to the plate 30. Plate 30 is provided with a back and forth extending slot 36 through which extends a bolt 37 which secures the plate to the underside of carrier 20. By loosening bolt 37 the weft detector can be adjusted rearwardly or forwardly relatively to carrier 20 and the support 17.

Extending forwardly from the detector finger 32 is a switch controlling finger 40 for cooperation with a plunger 41 forming part of an electric switch 42 secured to the under side of plate 30. The switch is so constructed that when the plunger is pushed in, or moved to the right as viewed in Fig. 2, the switch will be open, but when the detector moves to indicating position, shown in dotted lines Fig. 2, the finger 40 will move to the left, thereby permitting plunger 41 to move to the left to effect closure of a contact within the switch 42. When this switch is closed a loom controlling circuit including electric wires 43 and 44 is closed to effect a change in loom operation, such as weft replenishment.

The matter thus far described may be of common construction and operates in the usual

manner. When the shuttle S in the shuttle box 45 is to be replenished the transfferer arm 21 descends to push a new bobbin into the shuttle, the old bobbin passing downwardly through a slot 43 in the lay 47. At the same time the carrier 28, detector plate 30, and detector finger 32 are moved forwardly by lug 45, and it is incident to this forward motion that the detector finger is likely to rock on its pivot stud 31 and move finger 40 to the left, Fig. 2, and permit plunger 41 to enable switch 42 to give a false indication of weft exhaustion.

The object of the present invention is to provide means which would prevent the detector finger from having a false indication when it is moved forwardly due to descent of the transfferer arm, and in carrying the invention into effect I provide a lock lever 50 pivoted at its right end as viewed in Fig. 2 to a stud or screw 51 fastened to and extending upwardly from the plate 30. A wing 52 is secured to the lever 50 and extends upwardly therefrom for engagement with a positioning screw 53 adjustable back and forth in the stationary support 17. A spring 54, shown in Fig. 2 as of the resilient wire type, has an end 55 thereof received by a groove 56 in the forward edge of the lever 50 to be held in operative relation with respect to the lever. The spring extends down through a perforation 57 in the plate 30 and is then bent in the form of an eye 58 and held by the head 59 of a screw 60 tapped into the under side plate 30. The effect of the spring is to urge lever 50 in a clockwise direction as viewed in Fig. 2. Spring 55 is weaker than spring 24 so that the latter is always able to overpower the weaker spring and maintain the detector in normal detecting position on non-replenishing beats of the loom.

Lever 50 is provided with a detector or notch 61 to receive a lug 62 on the forward part of finger or arm 40 when the lever is in locking position. The left side of notch 61, Fig. 2, is defined by a shoulder 63 on lever 50, and a stop wall 64 on the lever is at the front of the notch.

Under normal conditions the parts will be in the position shown in Fig. 2, lever 50 being held in forward non-locking position due to the fact that spring 24 while acting to maintain the detector in rear position causes the wing 52 to engage the stationary control member or screw 53 and thus hold the lever 50 in open or non-locking position, as shown in Fig. 2. On a weft replenishing beat of the loom, however, when plate 30 moves forwardly as already described the lever 50 also moves forwardly, but the screw 53 remains stationary and as the pivot or stud 51 advances the screw 53 becomes a fulcrum around which the lever can rock until lug 62 enters the notch 61 as shown in Fig. 3. The shoulder 63 is then at the left of lug 62 and the detector finger cannot rock in a direction to give a false indication of weft exhaustion and the switch 42 remains open. During continued forward motion of plate 30 the lock lever moves away from screw 53 and wall 64 by its engagement with the front of lug 62 prevents further turning of the lever on plate 30.

As the lay moves rearwardly subsequent to a replenishing operation the spring 24 returns the detector to its normal position, and in doing so causes screw 53 to effect rocking of lever 50 relatively to plate 30 in a counter-clockwise direction around the pivot stud 51 and return the lever to its normal non-locking position shown in Fig. 2.

From the foregoing it will be seen that the

invention sets forth simple means for preventing an electrical side slipping weft detector from giving a false indication by providing a lock lever normally in non-locking position when the detector is in rear position but moved to locking position relatively to the detector finger when the detector mechanism is moved forwardly by the transfferer arm. Lever 50 moves into locking position incident to forward motion of plate 30 and no additional mechanism is needed to effect movement of the lever to locking position. Screw 53 can be adjusted to regulate the time of locking of the detector finger should the plate 30 be adjusted back or forth relatively to carrier 20 by means of bolt 36.

Having thus described the invention it will be seen that changes and modifications of the foregoing specific disclosure may be made without departing from the spirit and scope of the invention.

20 What is claimed as new is:

1. In weft detecting mechanism for a loom having a transfferer arm which operates on weft replenishing beats of the loom, a weft detector moved forwardly by the transfferer arm on replenishing beats of the loom, a side slipping detector finger on the weft detector normally in nonindicating position but tending to have a false side slipping indicating movement when the weft detector is moved forwardly by the transfferer arm, a lock lever for said finger pivoted on the weft detector, a stationary control member normally engaging said lever and preventing the latter from moving to locking position relatively to said finger when the weft detector is in normal position, and resilient means tending to move the lock lever into locking position relative to said finger, said weft detector when moved by the transfferer arm moving the lever relatively to said control member and said resilient means thereupon moving the lever into locking relation with the finger to prevent the latter from having a false side slipping movement.

2. In an electrically indicating side slipping

45 weft detector mechanism for a loom having a transfferer arm which operates on weft replenishing beats of the loom, a weft detector normally in detecting position but moved from such position by the transfferer arm on a weft replenishing beat of the loom, a detector finger pivoted on said weft detector normally in nonindicating position but tending to move the indicating position when the weft detector is moved by the transfferer arm, an electric switch on said weft detector, an arm 50 on said detector finger normally maintaining the switch open, a lock lever pivoted on said weft detector moving with the latter and formed to have holding engagement with the arm, a stationary control member engaging the lock lever and normally maintaining the latter in nonlocking position with respect to said arm, and means moving the lever into locking relation with said arm when the weft detector is moved by the transfferer arm and moves the lock lever relatively to said stationary control member.

3. In weft detecting mechanism for a loom having a transfferer arm which operates on weft replenishing beats of the loom, a stationary support, a carrier movable backwardly and forwardly 70 relatively to said support, a spring normally holding the carrier in rear position, a side slipping weft detecting finger supported by and moving backwardly and forwardly with the carrier, said transfferer arm on a replenishing beat of the loom causing forward movement of the carrier

and finger and the latter tending due to said movement to have a false side slipping motion, a lock lever mounted for pivotal motion relative to the carrier and moving backwardly and forwardly therewith, a stationary control member normally engaging the lock lever and holding the latter in nonlocking position with respect to said finger, and a spring normally urging the lever toward locking position and against said control member and exerting less force than the first named spring, said carrier when moved forwardly by the transferer arm overpowering the first named spring and enabling the second spring to move the lock lever into locking relation with respect to said finger to prevent the latter from having a false side slipping motion.

4. In weft detecting mechanism for a weft replenishing loom, a stationary support, a carrier movable backwardly and forwardly relatively to the support, a plate secured to said carrier, a side slipping weft detector finger pivoted on the plate, a lock lever pivoted on the plate normally tending to move into locking position with respect to said finger, the carrier and plate and finger having a forward movement on weft replenishing beats of the loom and said finger tending to have a false side slipping motion due to said movement, a stationary control member for said lock lever adjustable backwardly and forwardly with respect to said support and normally preventing said lever from moving into locking relation with said finger, and holding connections between the carrier and plate by which said carrier and plate are adjustable with respect to each other in a back and forth direction, said plate when having said forward movement moving said lever relatively to said control member and enabling said

lever to move into locking relation with respect to the finger to prevent the latter from having a false side slipping movement.

5. A weft detector supporting plate for a weft replenishing loom having a stationary control member and a carrier which moves forwardly on weft replenishing beats of the loom, said plate having a side slipping weft detecting finger pivoted thereon and having a lock lever pivoted thereon and supporting a spring normally tending to move the lock lever into locking relation with respect to said detector finger, said lever constructed to engage said control member and said plate constructed for attachment to said carrier.

6. In weft detecting mechanism for a weft replenishing loom, a stationary control member, a weft detector having a forward movement on weft replenishing beats of the loom, a side slipping detector finger, a pivotal connection between the finger and the weft detector, an arm on said finger extending forwardly from said pivotal connection, a lock lever pivoted on the weft detector having a stop wall and a shoulder, and resilient means normally tending to move the lock lever into locking relation with respect to said arm but prevented from doing so by said control member, said weft detector when moving forwardly moving said lock lever and detector finger forwardly relatively to said control member and said resilient means thereupon moving said stop wall rearwardly against said arm and moving said shoulder into position to prevent side slipping motion of the finger relatively to the weft detector.
